BAG FILLING, CLOSING, AND SEALING
MACHINE

Howard G. Allen and William O. Sims, Niagara Falls, N. Y., assignors to Bagpak, Inc., New York, N. Y., a corporation of Delaware

Application December 6, 1941, Serial No. 421,858

10 Claims. (Cl. 226—51)

This invention relates to new and useful improvements in bag filling and closing machines of the type in which filled bags are presented in uniformly spaced relation to a straight line conveyer as an incident to closing operations and, particularly, seeks to provide novel mechanisms to maintain the same spacing between successively presented bags even when bags of different widths are employed on successive filling runs.

This invention is particularly adapted to be employed in connection with bag filling and closing machines of the type disclosed in U. S. Letters Patent 2,054,279 granted September 15, 1936, to Howland F. Briggs. In machines of this nature, a rotary filling turret is provided which includes a plurality of radially disposed filling spouts and bag gripping elements associated therewith. The circumferential spacing between adjacent sets of filling spouts and bag grippers is normally designed to provide minimum edge to edge spacing between adjacent bags held thereby. After the thus held bags are filled, they are successively transferred to a straight line conveyer operated at a linear speed equal to the peripheral speed of the turret and which effects the presentation of the filled bags to the continuously operable, closing and sealing mechanisms of the machine. In the event that bags of less width than those for which the spacing of the filling turret was originally designed are desired to be filled it is believed to be obvious that, as a result of such decreased bag width, the edge to edge spacing between adjacent bags on the turret will be increased. Thus, when such narrower bags are presented by the straight line conveyer to the closing and sealing mechanisms, the increased spacing between the bags will result in substantially increased wastage of the closing and sealing media. This invention provides means for reducing the spacing between bags of such narrower widths to the desired spacing to thereby prevent wastage of the closing media.

It is therefore an object of this invention to provide, in a bag filling and closing machine of the type employing a rotary filling turret and a straight line closing and sealing unit operable synchronously therewith and adapted to receive bags successively presented thereto from the turret, means for so correlating the linear speed of operation of the take-off conveyer of the closing and sealing unit with the peripheral speed of the turret that substantially identical spacing may be maintained between bags successively presented to the take-off conveyer regardless of the width of bags used on successive runs.

Another object of this invention is to provide a machine of the character stated in which the linear speed of the take-off conveyer is normally equal to the peripheral speed of the turret and

in which means are provided to reduce the speed of the take-off conveyer at properly timed intervals as an incident to the maintaining of proper spacing between bags carried by the take-off conveyer.

Another object of this invention is to provide a machine of the character stated in which the speed variations of the take-off conveyer are effected through control mechanisms continuously operable at a definite speed ratio with respect to the speed of rotation of the turret.

Another object of this invention is to provide a machine of the character stated in which the closing and sealing mechanisms are provided with devices adapted to effect feeding of the mouth portions of the bag and which feeding operation is effected at the same rate of speed as the linear travel of the take-off conveyer and in which the conveyer speed control mechanisms are also effective to cause a corresponding variation in the speed of operation of the closing and sealing mechanisms.

Another object of this invention is to provide a machine of the character stated in which the speed variations of the take-off conveyer are effected through the medium of a continuously operable two-speed clutch controlled mechanism.

Another object of this invention is to provide a machine of the character stated in which the conveyer speed control mechanisms which actuate the two-speed clutch are so designed that shifting of the clutch from one speed controlling position to another will be effected without imparting any substantial shock to the closing and sealing mechanisms.

Another object of this invention is to provide a machine of the character stated in which the conveyer speed control mechanisms are adjustable to vary the timing of operations of the clutch whereby the machine may be readily adapted for use in connection with bags having different widths from those for which the machine was initially adjusted.

Another object of this invention is to provide a machine of the character stated in which the speed control mechanisms thereof are simple in design, rugged in construction and economical to manufacture.

With these and other objects in view, the nature of which will become more apparent, the invention will be more fully understood by reference to the drawings, the accompanying detailed description, and the appended claims.

In the drawings:

Fig. 1 is a somewhat fragmentary top plan view, partly in section, of a bag filling and closing machine constructed in accordance with this invention;

Fig. 2 is a front elevational view of the closing

and sealing section of the machine taken along line 2—2 of Fig. 1;

Fig. 3 is a vertical transverse section taken along line 3—3 of Fig. 1;

Fig. 4 is a top plan view of the mechanism illustrated in Fig. 3;

Fig. 5 is an enlarged elevational view of the speed control mechanism;

Fig. 6 is a fragmentary elevational view of the speed control mechanism and shows one speed controlling position of the two-speed clutch actuating linkage;

Fig. 7 is a view similar to Fig. 6 but shows the other position of the two-speed clutch actuating linkage;

Fig. 8 is a detailed section taken along line 8—8 of Fig. 6;

Fig. 9 is a detailed section taken along line 9—9 of Fig. 7;

Fig. 10 is a vertical transverse section of the speed control mechanism illustrated in Fig. 5 and taken along line 10—10 thereof;

Fig. 11 is an enlarged elevational view of the two-speed clutch mechanism together with its associated driving and driven connections, the cover of the housing being removed;

Fig. 12 is a horizontal section taken along line 12—12 of Fig. 11;

Fig. 13 is a vertical section taken along line 13—13 of Fig. 11; and

Figs. 14 and 15 are enlarged fragmentary sectional views of the two-speed clutch and illustrate the two operative positions of the clutch elements.

It will be seen in Fig. 1 of the drawings that the closing and sealing section of the machine is illustrated in detail and includes a sewing head A adapted to form a continuous line of stitches during operation of the machine and, thus, secure the mouths of successively presented filled bags, tape applying mechanism B adapted to continuously apply tape to the sewn bag mouths to seal the same, a horizontal slatted conveyer C adapted to support and advance the filled bags, and a set of horizontally opposed conveyer chains D adapted to engage the mouth portions of the filled bags and control the same during advance of the bags through the closing and sealing section of the machine, all of the above mechanisms being supported on a main frame generally indicated E.

The main supporting frame E is provided at one end with a laterally extending portion adapted to support a filling turret generally indicated at F (only a portion thereof being illustrated herein) and from which filled bags are adapted to be received by the closing and sealing section of the machine. In the complete operative installation of machines of this nature, a main hopper is provided which supplies material to a series of weigh-buckets for uniformly measuring out consecutive charges of the material. The weigh-buckets discharge the uniform quantities of material into the bags held on the turret through filling nozzles, one of which is indicated at G in Fig. 4 of the drawings. By reference to the above mentioned U. S. Letters Patent 2,054,279, it will be observed that the turret structure as a whole includes a plurality of radially disposed filling nozzles immediately below which is located a corresponding number of sets of bag engaging elements including spaced grippers 5, 5 (see Figs. 3 and 4 of the drawings herein) which are adapted to hold and manipulate the mouth portion of a bag as an incident to

the filling thereof. It will be noted that the manipulative movements of the grippers may include a contractive movement which is effective to partially open the mouth of a bag held thereby, and a bodily vertical movement which is effective to apply the thus-opened bag mouth to the associated filling nozzle, and a final downward vertical movement effective to return the filled bag to its initial position relative to the turret. The turret is constantly rotated at uniform speed and an operator normally stands at the position indicated S in Fig. 1 from which he applies bags to the grippers. As the applied bags are carried by the grippers, their lower ends become slidably engaged with an arcuate vibrator plate 7 positioned along the path of travel of the bag and effective to support the bags during filling and to cause compacting of the charge of material being received by the bags. A plurality of radially disposed arms 9 are carried by the turret and are disposed in a plane slightly above that of the arcuate vibrator plate 7 and are effective to control the lower depending ends of the bags during filling and to prevent angular displacement of the bags relative to the grippers. After the bags have been filled, the continued rotation of the turret causes the path of travel of the bags to coincide with the longitudinal axis of the closing and sealing section of the machine and, at this point, the grippers and bags become disengaged through the action of a gripper releasing cam 10 secured to frame E in substantial registry at such point of coincidence, and the body portions of the bags become supported by the slat conveyer C and the flattened mouth portions of the bags become engaged between the upper conveyer chains D preparatory to closing and sealing operations.

When bags of maximum permissive width are filled, closed and sealed on machines of this type, the edge to edge spacing between bags carried by the turret is normally proper for efficient and economical closing and sealing. Consequently, the closing and sealing section of the machine may be operated at a linear speed equal to the peripheral speed of the turret. However, when bags of lesser widths are to be filled, closed and sealed on the same machine, the edge to edge spacing between bags on the turret is greater than that required and means must be provided to effect a reduction of the spacing between the bags after they are released by the grippers and prior to the time at which closing and sealing operations begin in order to avoid unnecessary wastage of the closing and sealing media as hereinbefore stated.

To this end the main frame E is provided with a vertically disposed channel piece 11 upon which a main driving motor 13 is adjustably mounted through the medium of a supporting plate 15 and hand-screw adjusting means 17. The motor is provided with a pulley 19 and is adapted to transmit power to a gear box generally indicated at 21 through belt and pulley connections indicated at 23. The gear box 21 is rigidly secured to a vertical post 25 forming part of the main frame E and includes a continuously rotating horizontal shaft 27 having its ends projecting beyond the gear box and one of which carries the pulley connections 23 by which power is received from the motor. A duplex clutch unit generally indicated at 29 is carried within the gear box 21 on the shaft 27 and is adapted to drive an upper shaft 31 at either of two pre-

determined speeds of rotation through the medium of a small sprocket gear 33, sprocket chain 35 and a larger sprocket gear 37 or through a relatively large sprocket gear 39, sprocket chain 41 and smaller sprocket gear 43 as clearly shown in Fig. 11 of the drawings. The exact functions and operation of the duplex clutch and of the alternately usable sets of sprocket and chain connections for driving the upper shaft 31 will be hereinafter described in detail.

The other projecting end of the shaft 21 is provided with a pulley 45 which is adapted to drive a horizontal shaft 47 carried by the main frame through pulley and belt connections indicated at 49. The shaft 47 is operatively connected to the input side of a right angle speed reducer or other appropriate type of gear box 51 by which power from the shaft 47 may be transmitted to the rotary filling turret. The output side of the speed reducer is provided with a shaft 53 disposed at right angles to the shaft 47 and which is operatively connected with the filling turret through worm and gear connections generally indicated at 55 (see Fig. 1 of the drawings herein). Thus, power from the motor 13 is adapted to be continuously transmitted through the shaft 27 of the gear box, the horizontal lower frame shaft 47, the speed reducer or gear box 51, the shaft 53 and the worm and gear connections 55 to the filling turret to continuously rotate the same at a slow uniform speed.

The sewing mechanism A is provided with a horizontal shaft 57 disposed with its axis parallel to the longitudinal axis of the closing and sealing section of the machine and is provided at one end with a pulley 59 which is operatively connected to the upper shaft 31 of the gear box 21 through the medium of a belt 61 and a pulley 63 secured to the shaft 31 (see Figs. 1 and 2 of the drawings herein). The other end of the shaft 57 terminates adjacent the discharge end of the closing and sealing section of the machine and is provided with a bevel gear 65 rigidly affixed thereto. The gear 65 meshes with a corresponding bevel gear 67 secured to one end of a short horizontal laterally extending shaft 69 journalled on the frame E above the plane of the upper conveyer chains D. The shaft 69 is also provided with a second bevel gear 71 rigidly affixed thereto and meshing with a corresponding bevel gear 73 secured to the upper end of a vertical shaft 75 journalled on the frame E adjacent the end thereof. A spur gear 77 is affixed to the shaft 75 immediately below the bevel gear 73 and meshes with a similar spur gear 79 affixed to a short vertical shaft 81 journalled on the frame E in properly spaced relation to the shaft 75. Each of the vertical shafts 75 and 81 is provided with a sprocket gear 83 located in the plane of the chains of the upper conveyer D. A pair of similar sprocket gears 85 are mounted adjacent the intake end of the closing and sealing section of the machine. An endless sprocket chain 87 is engaged around each pair of sprocket gears 83, 85 and it will be apparent by reference to Figs. 1 and 3 of the drawings that the adjacently disposed straight portions of the chains 87 are spaced a distance such that the mouth portions of filled bags presented thereto from the filling turret will be received therebetween and advanced thereby.

The lower end of the shaft 75 is provided with a bevel gear 89 which meshes with a similar gear 91 carried by a short laterally extending horizontal shaft 93. The shaft 93 carries a

sprocket gear 95 which is adapted to drive the horizontal slat conveyer C through the medium of a sprocket chain 97 and a sprocket gear 99 as indicated in Fig. 2 of the drawings.

5 It will be noted that the speed ratios between the respective sets of meshing gears together with the diametric ratios between the respective sets of driving and driven sprocket gears are all so correlated that the linear speed of advance 10 of the slatted conveyer C, the upper chain conveyer D, the effective speed of feed of the sewing mechanism A and the effective speed of feed 15 of the tape applying mechanism B are all equal; and it will be further noted that since the source 20 of power of all of these elements and mechanisms stems from the gear box 21, any variation 25 in the speed of rotation of the shaft 31 therein will produce a corresponding change in the speed of operation of all the above mentioned 30 elements and mechanisms. In other words, the effective operative speed of the mechanisms in the closing and sealing section of the machine may be varied as a whole by varying the speed of the shaft 31. Therefore, when it is 35 found to be desirable or necessary to have the edge to edge spacing between adjacent bags in the closing and sealing section of the machine less than the spacing between adjacent bags on the uniformly rotating filling turret, the mechanisms 40 of the closing and sealing section can be slowed to a speed below the speed of the turret for a short period of time after each bag has been transferred from the filling turret and the grippers thereof have been released. This slowing of the closing and sealing section of the machine permits the next succeeding bag on the constantly and uniformly moving turret to overtake the previously transferred bag carried by the conveyers of the closing and sealing section. 45 As this next succeeding bag approaches the position at which its transfer to the closing and sealing section takes place, the mechanisms of that section are again speeded up to equal the peripheral speed of the turret and the bag transferring actions will then be fully and properly synchronized.

In order that the speed changes in the closing and sealing section of the machine can be automatically effected and synchronized with the 50 operation of the filling turret, the shaft 53 of the right angle gear box 51 is provided with a sprocket gear 101 which, through a sprocket chain 103, drives a somewhat larger sprocket gear 105 affixed to a laterally extending shaft 107 forming part of a mechanism generally designated 109 for controlling the duplex clutch 29 in the gear box 21. The clutch control mechanism includes a housing having a back plate 111 secured to the main frame E and in which the shaft 107 is journalled. The inner end of the shaft 107 carries a sprocket gear 113 which, through a sprocket chain 115, drives a larger sprocket gear 117 rotatably carried by a shaft 119. A clutch-actuating cam generally indicated at 121 having a cam supporting disk 123 and a hub 125 is rigidly affixed to the sprocket gear 117 and is rotatably carried by the shaft 119. The edge portion of one face of the disk 123 is cut back to form an annular clamping shoulder 127 (see Figs. 8 and 9) and this shoulder is in turn provided with an annular groove 129 for receiving position-determining elements of a pair of lug cams to be hereinafter described in detail.

A lug cam 131 projects outwardly in a generally radial direction from the disk 123 and is adjust-

ably secured thereto through the medium of a pair of position-determining studs 133 which are engaged in the annular groove 129 and an L-shaped clamping member 135 which is releasably secured to the lug cam by clamping screws 137. It will be noted that the clamping element 135 together with the associated portion of the lug cam 131 form a pair of clamp jaws which span the edge portion of the cam supporting disk 123 so that when the set screws 137 are tightened the lug cam as a whole will be rigidly clamped to the supporting disk. The outer end of the lug cam 131 is provided with a laterally extending portion 139, the inner edge portion of which is contoured to define a cam face 141 adapted to engage and move the clutch-actuating linkages in one direction.

A generally similar lug cam 143 is also secured to the cam supporting disk 123 through the medium of position-determining studs 145 engaged in the annular groove 129, L-shaped clamping member 147 and clamping screws 149. The lug cam 143 is likewise provided with a laterally projecting portion 151, the outer edge portion of which is contoured to define a cam face 153 adapted to move the clutch-actuating linkages in a direction opposite to that effected by the lug cam 131.

The back plate 111 is provided with a boss 155 in which a rock shaft 157 is journalled. The inner end of the rock shaft 157 carries an upstanding pitman 159 rigidly secured thereto and the free end of which is provided with a laterally offset roller cam follower 161 rotatably carried by a pivot stud 163. The outer end of the rock shaft 157 which projects rearwardly of the back plate 111 carries a downwardly extending pitman 165 rigidly affixed thereto. The lower end of the pitman 165 is pivotally connected as at 167 to one end of a connecting link 169. The other end of the link 169 is pivotally connected as at 171 to the lower end of a depending pitman 173 affixed to the rear end of a rock shaft 175 journalled in the gear box 21 adjacent the bottom thereof.

A yoke 177 is rigidly affixed to the rock shaft 175 and includes a pair of upstanding arms 179, the upper ends of which pivotally engage a pair of diametrically opposed trunnions 181 rigidly carried by a clutch actuating collar 183. Thus, rocking of the shaft 175 will cause axial movement of the collar 183. It will be seen in Fig. 14 of the drawings that axial movement of the collar 183 to the left will, through the link and roller connections 185 and clutch plate engaging sleeve 187, effect a compressing together of the several plates included in the left hand clutch unit of the duplex clutch. When these plates are thus brought into surface contact in this manner, the driving power will be transmitted from the shaft 27 through the clutch plates to the sprocket gear 39 from which the shaft 31 is then driven. Rocking of the shaft 175 in the opposite direction will produce an axial movement of the collar 183 to the right and, as shown in Fig. 15 of the drawings, the collar will, through the roller and link connections 189 and the clutch plate engaging sleeve 191, effect a compressing together of the several plates of the right hand unit of the duplex clutch to thereby transmit power from the shaft 27 through the clutch plates to the sprocket gear 33 from which the shaft 31 will then be driven. It will be noted that the right and left individual clutch units of the duplex clutch are alternately engageable and that, since

5 this is the case, the shaft 31 will be driven at whichever of the two speed ratios are available through the sprockets 39 and 43 on the one hand or through the sprockets 33 and 37 on the other hand.

10 The yoke 177 may have associated with it a sector plate 193 having three spaced radial notches formed in the periphery thereof. The notched periphery of the sector 193 is adapted to be engaged by a roller follower 195 rotatably mounted intermediate the ends of an arm 197. One end of the arm 197 is pivotally connected to the housing of the gear box 21 as at 199 and the other end of the arm 197 is constantly and yieldably biased downwardly through the medium of an adjustably connected tension spring biasing means generally indicated 201. Thus, engagement of the roller follower 195 with the notches in the sector plate 193 will maintain the yoke 177 in the three positions into which it may be moved, namely, the two active clutch operating positions and an intermediate neutral position in which neither of the units of the duplex clutch is operative to drive the shaft 31. Thus, it will be apparent that rocking of the shaft 157 by the pitman 159 under the influence of the lug cams 131 and 143 of the clutch control mechanism will result in a corresponding axial movement of the clutch actuating collar 183 of the duplex clutch unit to thereby selectively control and cause driving of the shaft 31 together with the elements which are driven therefrom at those speeds which have been found desirable to produce the result heretofore mentioned.

15 30 35 As it is believed that the description of the various mechanisms herein have been quite detailed, no detailed description of the operation will be given herein. However, a brief outline of the operation will be made in order that the coordination of the several mechanisms may be fully understood. When the machine is placed into operation the filling turret F is constantly rotated at a uniformly relatively slow speed through the connections heretofore described. 40 Initially, the mechanisms of the closing and sealing section of the machine operate at a speed substantially equal to the peripheral speed of the filling turret. Therefore, when a filled bag which is held by the grippers 5 of the turret approaches the point of coincidence with the longitudinal axis of the closing and sealing section of the machine, the gripper 5 which holds the top leading corner of the bag is released by engagement with the releasing cam 10 on the frame E and, simultaneously, the leading bottom corner of the bag becomes supported upon the slatted conveyer C. At the same time the leading edge of the collapsed mouth portion of the bag becomes engaged between the upper conveyer chains D and is gripped thereby. Continued advance of the turret and of the horizontal conveyer C and the upper conveyer chains D will cause the conveyer chains D to progressively grip the collapsed mouth portion of the bag across its entire width and when the gripper 5 which holds the trailing top corner of the bag reaches the point of coincidence with the longitudinal axis of the closing and sealing section of the machine, it is released by engagement with the releasing cam 10 whereupon the filled bag becomes placed entirely under the control of the mechanisms contained in the closing and sealing section of the machine. Thus, transfer of the bag from the rotary turret to the straight line closing and sealing section of the machine is perfectly synchronized. As soon as

the grippers 5 on the filling turret have released the bag mouth, or shortly thereafter, the lug cam 151 of the cam control mechanism 109 becomes effective to rock the pitman 159 to the right. This transmits a corresponding rocking motion to the left on the pitman 165, moves the connecting link 169 and the depending pitman 173 of the gear box 121 to the left and effects an axial movement to the right of the clutch control collar 183. This movement disengages the plates of the left hand unit of the duplex clutch and renders the same ineffective to drive the shaft 31 at the speed synchronizing the closing and sealing section of the machine with the filling turret and effects an engagement of the clutch plates of the right hand unit of the duplex clutch to drive the shaft 31 through the sprocket gears 33 and 37 and the sprocket chain 35 at a speed such that the mechanisms of the closing and sealing section of the machine will then be driven at a lesser speed. Thus, the horizontal slatted conveyer C, the upper conveyer chains D as well as the feeds of the sewing head and the tape applying mechanisms are all reduced. This reduction in speed is, of course, transmitted to the bags then being carried in that section of the machine while permitting the bags still being carried by the filling turret to travel at the initial or greater speed. Therefore, it is believed to be apparent that the next succeeding bag carried by the filling turret will catch up to the bag which has just been transferred to the closing and filling section of the machine. As this next succeeding bag on the turret approaches the point at which transfer therefrom to the conveyers of the closing and filling section of the machine is made, the lug cam 131 of the clutch control mechanism 109 will effect a rocking movement to the left of the pitman 159 and, through the linkage above described, will effect a corresponding movement to the left of the clutch-actuating collar 183. This disengages the right hand unit of the duplex clutch and reengages the left hand unit of the clutch to again effect a speed up of the mechanisms of the closing and sealing section of the machine to the speed equal to the peripheral speed of the turret. Thus, the two operative sections of the machine are again placed into perfect synchronization and the transfer of this next succeeding bag carried by the turret can be properly effected.

It will be observed that the amount of stitch forming thread and sealing tape which will be saved per bag through the employment of a filling and closing machine constructed in accordance with this invention will be equal to the difference between the edge to edge spacing of the bags as carried by the filling turret and the edge to edge spacing of the bags as they are handled in the closing and sealing section of the machine.

It may be noted that the length of time during which the mechanisms of the closing and sealing section of the machine are operated at the slower speed and at the higher speed may be readily varied in accordance with the demands of varying widths of bags employed on succeeding filling runs by the simple expedient of varying the angular spacing between the adjustable lug cams 131 and 143 carried by the disk 123 of the clutch control mechanism. Variation of the angular spacing between the adjustable lug cams 131 and 143 is made necessary as the result of operating upon bags of different widths on succeeding runs of the machine. As pointed out hereinabove, in order to secure maximum economy in the clos-

ing and sealing media, it is desirable that the edge to edge spacing between bags carried in the closing and sealing section of the machine be maintained at an optimum minimum distance. Therefore, variations in widths of bags operated upon in successive runs will produce a corresponding variation in the edge to edge spacing between such bags when carried by the turret and, consequently, the reduction in spacing as between bags on the turret and bags carried in the closing and sealing section of the machine may be either greater or lesser than the reduction of such spacing required on the machine as initially set up. Thus, in operating upon a certain size of bags, the turret and the mechanisms of the closing and sealing section operate at a one to one speed ratio during the time at which individual bags are transferred from the turret and after the transfer of each bag has been completely effected, the lug cam 143 causes reduction of speed of operation of the closing and sealing mechanisms. In another run, when bags of different widths are being operated upon, the one to one speed ratio between the turret and closing and filling section will be still maintained during the times at which transferring operations of individual bags are effected but the lug cam 143 may be differently angularly spaced from the lug cam 131 in order that the time at which the speed reduction of the closing and sealing mechanisms occurs will be changed whereby to result in the obtaining of the same optimum minimum edge to edge spacing between bags carried in the closing and sealing section of the machine.

In the event that bags of such great width are employed in the machine that there is no necessity for reducing the edge to edge spacing therebetween prior to the time at which the actual closing and sealing operations occur, the lug cam 143 can be removed from the clutch control mechanism and, consequently, the lug cam 131 will be initially effective to engage the plates of the left hand unit of the duplex clutch to drive the shaft 31 through the higher speed sprocket chain connections and will, thereafter, have no effect upon the operation of the machine. Therefore, the closing and filling section of the machine will always operate in perfect synchronization and at the same speed as the peripheral speed of the turret.

In connection with the effecting of the engagement of the clutch plates of the respective clutch units, it may be noted that the cam faces 141 and 153 of the lug cams 131 and 143 respectively are so contoured that movement of the pitman 159 in either direction is effected in, what might be termed, two stages, that is to say, the contour cams first impart movement to the pitman just sufficient to produce enough of a resultant movement in the clutch actuating collar 183 that one set of clutch plates will become disengaged and the other set of clutch plates will become partially engaged. The remaining portion of the contour of each of these cams is effective to produce in the pitman 159 the further movement necessary to effect the full and complete engagement of the clutch plates. Thus, by moving the clutch actuating collar 183 in a progressive manner like this, the engagement of the plates on either of the units of the duplex clutch is effected without imparting a sudden change of movement of rotation to the shaft 31 from which all of the mechanisms of the closing and sealing section of the machine are driven.

After the transfer of the bags is completed

From the rotary filling turret to the closing and sealing section of the machine in the manner above described, the mouth portions thereof are then subjected to the operations of the sewing head A which closes the mouth of each bag by a continuous line of stitching. It will be understood that since the machine as a whole is continuously operable and even though the mechanisms of the closing and sealing section of the machine are operable at either of two predetermined speeds, the line of stitching formed by the sewing head A will be continuous regardless of whether or not the mouth of a bag is being stitched. Thus, the intervening space between adjacent bags, after stitching has occurred, will be bridged by a line of stitching. Following the stitching operation, continued movement of the bags by the conveyer mechanisms of this section of the machine subjects the stitched mouths of the bags to the sealing operation which is effected by the application of adhesively secured tape applied through the mechanisms generally indicated at B. It may be here noted that at this point primary operations upon the bag have been completed, namely, the filling, closing by a line of stitching, and sealing by a strip of continuously applied adhesively secured tape. However, since the adjacent bags would still be connected together by the continuous line of stitching as well as by the continuously applied sealing tape, means are normally provided immediately after the tape applying mechanism and immediately prior to the point at which the filled, closed and sealed bags are discharged from the machine for severing the closing media at one or more points intermediate the trailing edge of one bag and the leading edge of the next following bag. As the structures of these severing devices are numerous and well known, none have been illustrated herein but it will be understood that such mechanisms are normally employed.

Thus, it will be seen that the herein described invention provides a novel bag filling and closing machine of the type employing a rotary filling turret and a straight line closing and sealing unit operable synchronously therewith and adapted to receive bags successively transferred thereto from the turret; in which means are provided for so correlating the linear speed of operation of a closing and sealing section of the machine with the peripheral speed of the turret that substantially identical spacing may be maintained between bags successively presented to the closing and sealing section regardless of the width of bags employed on successive runs; in which the spacing between bags is regulated through varying the speed of the closing and sealing section of the machine with respect to the peripheral speed of a turret in which such speed variations are effected through the medium of control mechanisms continuously operable at a definite speed ratio with respect to the speed of rotation of the turret; and in which the speed control mechanisms are adjustable to vary the timing of operations whereby the machine may be readily adapted for use in connection with bags having different widths from those for which the machine was initially adjusted.

We claim:

1. In a bag filling and closing machine wherein is provided a rotary filling turret adapted to hold a plurality of circumferentially spaced bags to be filled, means for supplying predetermined charges of material to said bags, means for con-

stantly rotating said turret at a uniform speed, a conveyer adapted to receive filled bags from said turret and advance the same, and continuously operable bag mouth closing and sealing mechanisms associated with said conveyer and having speeds of operation equal to the speed of advance of said conveyer; the combination of means effective to drive said conveyer and said closing and sealing mechanisms at effective speeds equal to the peripheral speed of said turret during the times at which individual bags are being transferred therefrom to said conveyer, a timing device driven with said turret at a predetermined ratio with respect to the speed of rotation of said turret, and means under the control of said timing device effective after each such bag has been transferred to said conveyer to reduce the speed of said conveyer and said closing and sealing mechanisms whereby the next succeeding bag held by said turret will catch up to the preceding bag on said conveyer and the edge to edge spacing therebetween will be less than the edge to edge spacing between bags on said turret and substantial savings of the closing and sealing media will result.

2. In a bag filling and closing machine wherein is provided a rotary filling turret adapted to hold a plurality of circumferentially spaced bags to be filled, means for supplying predetermined charges of material to said bags, means for constantly rotating said turret at a uniform speed, a conveyer adapted to receive filled bags from said turret and advance the same, and continuously operable bag mouth closing and sealing mechanisms associated with said conveyer and having speeds of operation equal to the speed of advance of said conveyer; the combination of means including a changeable speed mechanism for driving said conveyer and said closing and sealing mechanisms, a first means under the control of said turret for automatically adjusting said changeable speed mechanism to drive said conveyer and said closing and sealing mechanisms at effective speeds equal to the peripheral speed of said turret during the times at which individual bags are being transferred therefrom to said conveyer, and a second means under the control of said turret for automatically adjusting said changeable speed mechanism after each such bag has been transferred to said conveyer to reduce the speed of said conveyer and said closing and sealing mechanisms whereby the next succeeding bag held by said turret will catch up to the preceding bag on said conveyer and the edge to edge spacing therebetween will be less than the edge to edge spacing between bags on said turret and substantial savings of the closing and sealing media will result.

3. In a bag filling and closing machine wherein is provided a rotary filling turret adapted to hold a plurality of circumferentially spaced bags to be filled, means for supplying predetermined charges of material to said bags, means for constantly rotating said turret at a uniform speed, a conveyer adapted to receive filled bags from said turret and advance the same, and continuously operable bag mouth closing and sealing mechanisms associated with said conveyer and having speeds of operation equal to the speed of advance of said conveyer; the combination of means including a changeable speed mechanism for driving said conveyer and said closing and sealing mechanisms, a first means under the control of said turret for automatically adjusting said changeable speed mechanism to drive said conveyer and said closing and sealing mechanisms

at effective speeds equal to the peripheral speed of said turret during the times at which individual bags are being transferred therefrom to said conveyer, and a second means under the control of said turret for automatically adjusting said changeable speed mechanism after each such bag has been transferred to said conveyer to reduce the speed of said conveyer and said closing and sealing mechanisms whereby the next succeeding bag held by said turret will catch up to the preceding bag on said conveyer and the edge to edge spacing therebetween will be less than the edge to edge spacing between bags on said turret and substantial savings of the closing and sealing media will result, said first and second means being adjustable with respect to each other in accordance with the spacing between bags on said turret to establish a desired spacing between bags on said conveyer.

4. In a bag filling and closing machine wherein is provided a rotary filling turret adapted to hold a plurality of circumferentially spaced bags to be filled, means for supplying predetermined charges of material to said bags, means for constantly rotating said turret at a uniform speed, a conveyer adapted to receive filled bags from said turret and advance the same, and continuously operable bag mouth closing and sealing mechanisms associated with said conveyer and having speeds of operation equal to the speed of advance of said conveyer; the combination of means including a changeable speed mechanism for driving said conveyer and said closing and sealing mechanisms at effective speeds equal to the peripheral speed of said turret during the times at which individual bags are being transferred therefrom to said conveyer, and means including a cam constantly rotatable at a predetermined ratio with respect to the speed of rotation of said turret for automatically adjusting said changeable speed mechanism after each such bag has been transferred to said conveyer to reduce the speed of said conveyer and said closing and sealing mechanisms whereby the next succeeding bag held by said turret will catch up to the preceding bag on said conveyer and the edge to edge spacing therebetween will be less than the edge to edge spacing between bags on said turret and substantial savings of the closing and sealing media will result.

5. In a bag filling and closing machine wherein is provided a rotary filling turret adapted to hold a plurality of circumferentially spaced bags to be filled, means for supplying predetermined charges of material to said bags, means for constantly rotating said turret at a uniform speed, a conveyer adapted to receive filled bags from said turret and advance the same, and continuously operable bag mouth closing and sealing mechanisms associated with said conveyer and having speeds of operation equal to the speed of advance of said conveyer; the combination of means including a changeable speed mechanism for driving said conveyer and said closing and sealing mechanisms at effective speeds equal to the peripheral speed of said turret during the times at which individual bags are being transferred therefrom to said conveyer, and means including a cam constantly rotatable at a predetermined ratio with respect to the speed of rotation of said turret for automatically adjusting said changeable speed mechanism after each such bag has been transferred to said conveyer to reduce the speed of said conveyer and said closing and sealing mechanisms whereby the next succeeding bag held by said turret will catch up to the preceding bag on said conveyer and the

edge to edge spacing therebetween will be less than the edge to edge spacing between bags on said turret and substantial savings of the closing and sealing media will result, said last named 5 means being adjustable with respect to the spacing between bags on said turret to establish a desired spacing between bags on said conveyer.

6. In a machine of the class described, the combination of a rotary turret adapted to hold a plurality of circumferentially spaced bags, means for constantly rotating said turret at a uniform speed, a conveyer adapted to receive bags from said turret and advance the same, means associated with said conveyer and operable at a speed necessarily 10 related to the speed of said conveyer for performing an operation upon said bags as they are advanced by said conveyer, means for driving said conveyer and its associated means at effective speeds equal to the peripheral speed of said turret during the times at which individual bags are being transferred from said turret to said conveyer, a timing device driven with said turret at a predetermined ratio with respect to the speed of rotation of said turret, and means under the control 15 of said timing device effective after each such bag has been transferred to said conveyer to reduce the speed of said conveyer and the means associated therewith whereby the next succeeding bag held by said turret will catch up to the preceding bag on said conveyer and the edge to edge spacing therebetween will be less than the edge to edge spacing between bags on said turret.

7. In a bag filling and closing machine, a rotary filling turret adapted to hold a plurality of circumferentially spaced bags to be filled, means for supplying predetermined charges of material to said bags, means for constantly rotating said turret at a uniform speed, a conveyer adapted to receive filled bags from said turret and advance the same, continuously operable bag mouth closing and sealing mechanisms associated with said conveyer and having speeds of operation equal to the speed of advance of said conveyer, means effective to drive said conveyer and said closing and sealing 20 mechanisms at effective speeds equal to the peripheral speed of said turret during the times at which individual bags are being transferred therefrom to said conveyer, a timing device driven with said turret at a predetermined ratio with respect to the speed of rotation of said turret, and means under the control of said timing device effective after each such bag has been transferred to said conveyer to reduce the speed of said conveyer and said closing and sealing mechanisms whereby 25 the next succeeding bag held by said turret will catch up to the preceding bag on said conveyer and the edge to edge spacing therebetween will be less than the edge to edge spacing between bags on said turret and substantial savings of the closing and sealing media will result.

8. In a machine of the character described, a rotary turret adapted to hold a plurality of circumferentially spaced bags, means for constantly rotating said turret at a uniform speed, a conveyer adapted to receive bags from said turret and advance the same, continuously operable bag mouth closing and sealing mechanisms associated with said conveyer and having speeds of operation equal to the speed of advance of said conveyer, means effective to drive said conveyer and said closing and sealing mechanisms at effective speeds equal to the peripheral speed of said turret during the times at which individual bags are being transferred therefrom to said conveyer, a timing 30 device driven with said turret at a predetermined ratio with respect to the speed of rotation of said turret, and means under the control of said timing device effective after each such bag has been transferred to said conveyer to reduce the speed of said conveyer and said closing and sealing mechanisms whereby the next succeeding bag held by said turret will catch up to the preceding bag on said conveyer and the edge to edge spacing therebetween will be less than the edge to edge spacing between bags on said turret and substantial savings of the closing and sealing media will result.

75

ratio with respect to the speed of rotation of said turret, and means under the control of said timing device effective after each such bag has been transferred to said conveyer to reduce the speed of said conveyer and said closing and sealing mechanisms whereby the next succeeding bag held by said turret will catch up to the preceding bag on said conveyer and the edge to edge spacing therebetween will be less than the edge to edge spacing between bags on said turret and substantial savings of the closing and sealing media will result.

9. In a bag filling and closing machine, a rotary filling turret adapted to hold a plurality of circumferentially spaced bags to be filled, means for supplying predetermined charges of material to said bags, means for constantly rotating said turret at a uniform speed, a conveyer adapted to receive filled bags from said turret and advance the same, continuously operable bag mouth closing and sealing mechanisms associated with said conveyer and having speeds of operation equal to the speed of advance of said conveyer, means including a changeable speed mechanism for driving said conveyer and said closing and sealing mechanisms at effective speeds equal to the peripheral speed of said turret during the times at which individual bags are being transferred therefrom to said conveyer, and control means constantly operable at a predetermined ratio with respect to the speed of said turret for automatically adjusting said changeable speed mechanism after each such bag has been transferred to said conveyer to reduce the speed of said conveyer and said closing and sealing mechanisms

whereby the next succeeding bag held by said turret will catch up to the preceding bag on said conveyer and the edge to edge spacing therebetween will be less than the edge to edge spacing between bags on said turret and substantial savings of the closing and sealing media will result.

10. In a bag filling and closing machine, a rotary turret adapted to hold a plurality of circumferentially spaced bags, means for constantly rotating said turret at a uniform speed, a conveyer adapted to receive bags from said turret and advance the same, continuously operable bag mouth closing and sealing mechanisms associated with said conveyer and having speeds of operation equal to the speed of advance of said conveyer, means effective to drive said conveyer and said closing and sealing mechanisms at effective speeds equal to the peripheral speed of said turret during the times at which individual bags are being transferred therefrom to said conveyer, a timing device driven with said turret at a predetermined ratio with respect to the speed of rotation of said turret, and means under the control of said timing device effective after each such bag has been transferred to said conveyer to change the speed of said conveyer and said closing and sealing mechanisms whereby relative movement will occur between the next succeeding bag held by said turret and the preceding bag on said conveyer and the edge to edge spacing therebetween will become different than the edge to edge spacing between bags on said turret.
